UNITED STATES PATENT OFFICE.

WILLIAM N. TENNY AND CLARENCE J. TENNY, OF SHERMAN, CALIFORNIA.

COMBINATION LATCH HASP AND STAPLE.

1,312,931.

Specification of Letters Patent. Patented Aug. 12, 1919.

Application filed May 10, 1919. Serial No. 296,178.

To all whom it may concern:

Be it known that we, WILLIAM N. TENNY and CLARENCE J. TENNY, citizens of the United States, residing at Sherman, in the county of Los Angeles and State of California, have invented certain new and useful Improvements in Combination Latch Hasps and Staples, of which the following is a specification, reference being had to the accompanying drawings.

This invention relates to an improved combination latch hasp and staple particularly adapted for sliding and swinging doors, preferably barn and granary doors.

15 The invention aims to provide a very simple, efficient, and practical device of this kind, and which may be cheaply manufactured, and sold at a reasonable profit.

The invention further aims to provide an 20 improved hasp constructed from a single piece of sheet metal bent upon itself to provide a tongue for engagement with a keeper or staple, whereby the hasp, may be retained firmly in position, when the door is closed.

25 The invention further aims to provide a keeper or staple, so formed from a single piece of sheet metal, as to provide means to permit the keeper or staple to receive the tongue of the hasp, whether it is carried by 30 a swinging or sliding door, and yet retain the door in a closed position.

The invention further aims to provide a 35 combined latch and keeper device which may be used on the right or the left side of the door, permitting the device to perform its functions as efficiently on one side, as on the other.

40 While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the 45 scope of what is claimed.

The invention comprises further features and combination of parts, as will be herein-after set forth, shown in the drawings and 50 claimed.

In the drawings:

Figure 1 is a perspective view of the combined latch or hasp and staple constructed in accordance with the invention;

Fig. 2 is a plan view of the same; 55

Fig. 3 is a longitudinal sectional view on the line 3—3 of Fig. 1;

Fig. 4 is a perspective view of the latch;

Fig. 5 is a perspective view of the keeper;

Fig. 6 is a plan view of the blank which 60 forms the latch;

Fig. 7 is a plan view of the blank which forms the keeper; and

Fig. 8 is a detail view of a latch showing elongated openings instead of the circular 65 openings 13.

Referring to the drawings 1 designates a portion of a door, which may be either a sliding or swinging door, and secured by screws 2 to the outer face of the door is a 70 plate 3. One end of the plate is bent upon itself as shown at 4 to provide an ear 5, between which and the body of the plate a latch 6 is pivotally mounted upon the pin 7. This pin 7 has its opposite ends headed, as 75

shown, in order to prevent the removal of the pin. The latch 6 is constructed from a single piece of sheet metal preferably of the shape shown in Fig. 6, and in order to form the latch this sheet metal plate is bent upon itself as shown at 8, and again upon itself as shown at 9 and 10. As shown in Figs. 6 and 7, the locations of the bends 8, 9 and 10 are indicated by virtue of the scored lines. By bending the sheet metal plate at these 80

points, it will be noted that the latch is formed with a tongue 11. This tongue is formed owing to the portions 12 intermediate the bends 9, 8 and 10 being brought adjacent or flat against each other, as shown 90 in the longitudinal sectional view, Fig. 3. In order to make the tongue substantial, the opposite portions 12 are brought close together, and this can only be accomplished by imparting heavy successive hammer blows 95 on the bends 8, 9 and 10, that is in connection with an anvil. In order to obtain the best results the sheet metal plate, such as shown in Fig. 6, may be subjected to heat, so that the bends 8, 9 and 10 are more or less 100

positive, and the sides 12 will remain closer in contact. The opposite portions 12 are provided with openings 13, and it is to be noted that when the parts 12 are brought 5 closely in contact with each other, the openings 13 will register. It is to be noted that one set of openings 13 may receive the shackle of a padlock, in order to hold the tongue of the latch in engagement with the 10 keeper. As shown in Fig. 8, the tongue of the latch may be provided with an elongated opening 14, instead of the openings 13. This elongated opening 14 is constructed, by forming elongated openings in the opposite 15 portions 12, so that when the sheet metal is bent upon itself as at 8, 9 and 10, the openings in the parts 12 will register, and form the elongated opening 13.

The keeper is constructed from a single 20 piece of sheet metal, as shown in Fig. 7, and this keeper 16 may be secured by any suitable means, preferably screws 17, to the side of the barn or granary or other housing. This keeper is formed by bending the 25 sheet metal plate upon itself as shown at 18, 19 and 20. The bend 18 is more in the form of a curve, so that the opposite portions 21 of the keeper are spaced, for the reception of the tongue of the latch, when 30 dropped into engagement with the keeper. When making the bends 19 and 20, the parts 22 are disposed at right-angles to the opposite portions 21, and through these parts 22, the securing screws pass. The opposite 35 spaced portions 21 of the keeper are provided with registering openings 23, with which the openings 13, or the elongated slot of the tongue of the latch registers, for the reception of the shackle 24 of the padlock 40 25, thereby retaining the tongue of the latch in engagement with the keeper. It is to be noted that where the sheet metal plate is bent as at 19 and 20, the plate is also provided with elongated slots 26. These slots, 45 when the sheet metal plate is bent upon itself to form the spaced parts 12, register, whereby the tongue may enter the space between the opposed parts 21 of the keeper. In order to permit the tongue to readily 50 enter the space between the opposed parts 21, said parts at points adjacent the slots 26 are flared outwardly, as indicated at 27. It is also to be noted that the upper edges of the opposed parts 21 are inclined, in 55 order to permit the latch to ride upwardly thereon, provided the latch assumes a position to accomplish this function, so that the tongue may enter the space between the opposed parts 21. It is to be noted that 60 when the latch is closed, it overlies the securing screws of the latch supporting plate, which is carried by the door, and also overlies certain of the securing screws of the keeper, thereby preventing access to the securing 65 screws with a screw-driver, that is

when the latch is in engagement with its keeper, and a padlock passing through the opposite portions 21 and the tongue.

Furthermore, it will be noted that this particular form of latch and hasp may be 70 used either upon swinging or sliding doors. When used on a swinging door, the latch may be raised, and allowed to engage the opposite registering slots 26, so that the tongue of the latch may enter the space between the opposed parts 21. If the latch is used in connection with a sliding door, it will be noted that the latch may easily co-operate with the keeper, in a manner similar to that when the latch is employed in 75 connection with a swinging door.

The invention having been set forth, what is claimed as new and useful is:

1. The combination with a latch supporting plate adapted to be carried by a door, 80 of a keeper to be secured to and carried by the side of the housing adjacent one side of the door opening, said keeper comprising laterally extending spaced parallel parts having opposite registering openings, a latch 90 pivotally mounted upon the latch supporting plate and provided with a tongue adapted to enter the space between the opposite parallel parts of the keeper, said opposite parallel parts of the keeper and the tongue 95 having registering openings, for the reception of locking means.

2. The combination with a keeper to be secured to the side of a housing near one end of a door opening and provided with a 100 laterally extending keeper member, said keeper member comprising opposed parallel parts having registering openings, said keeper having opposed registering slots, of a latch pivotally carried by a door and 105 adapted to be swung downwardly to enter the slots, said latch having a laterally extending tongue, to enter the space between the opposite parallel parts of the keeper member, said tongue having an opening to 110 co-operate with the openings of the keeper member for the reception of the shackle of a padlock.

3. The combination with a keeper constructed from a single piece of sheet metal 115 bent upon itself to form opposite parallel spaced walls extending laterally, said walls having registering openings, and where said walls are bent from the body of the plate being provided with registering slots, means for securing the keeper to the side of the housing adjacent a door opening, of a latch supporting plate carried by the door, a latch pivotally mounted on the supporting plate, said latch being constructed from a single 120 piece of sheet metal, bent upon itself to form opposite parts, which, when the sheet metal plate of the latch is so bent, are brought flat against each other, thereby forming a tongue to enter the space between the spaced 125 130

parallel walls of the keeper, said tongue having an opening to register with the openings of the keeper, when the latch engages the registering slots, whereby the openings of the tongue and keeper may receive a padlock shackle, said latch being disposed and arranged, so as to overlie the securing means of the keeper.

In testimony whereof we hereunto affix our signatures in the presence of two witnesses.

WILLIAM N. TENNY.
CLARENCE J. TENNY.
